RADIO DIRECTION FINDER

Paul G. Hansel, Red Bank, N. J.

Application June 24, 1944, Serial No. 541,950

30 Claims. (Cl. 343—121)

(Granted under the act of March 3, 1883, as
amended April 30, 1928; 370 O. G. 757)

1

The invention described herein may be manufactured and used by or for the Government for governmental purposes, without the payment to me of any royalty thereon.

My present invention relates to radio direction finders, and more particularly, to direction finders of the electronic goniometer type.

One of the objects of my present invention is to provide a radio direction finder with a novel, omnidirectional, fixed antenna system, capable of operation over a relatively wide band of frequencies; which permits the taking of bearings on a plurality of sources of radio-frequency energy simultaneously; which avoids the structural problems and high costs ordinarily connected with directional systems; and which eliminates the tedious operating techniques and the inaccuracies usually associated with antenna systems requiring physical orientation.

Another object of my present invention is to provide a radio direction finder with an antenna system of such novel design as to decrease the number of transmission channels necessarily employed therein, thus reducing to a minimum, phasing and impedance-matching problems.

Still another object of my invention is to provide a novel, aperiodic, electronic goniometer, which includes means for modulating the output of the antenna system thereof, whereby the modulation envelope of each signal in the spectrum of signals contained in said output assumes a phase which is a function of the bearing of the source of each of such signals.

A further object of my present invention is to provide a novel bearing indicator for an electronic goniometer, in the form of a phase meter of the cathode-ray type, for comparing the phase of the output of the antenna system, modulated as above described, with the phase of the modulating energy; whereby an accurate bearing of the source of radio-frequency energy instantaneously under consideration is obtained; and this, even where the wave front of such radio-frequency energy is such as would ordinarily be considered unfavorable for direction finding.

A further object of my present invention is to provide such control over the indicator display as to enable modification of the normal pattern thereof on signals difficult to read so as to enhance accuracy of observation.

A still further object of my present invention is to provide a novel means for deriving the equivalent of an omnidirectional signal of suitable phase and amplitude for sense-determining

2

purposes, without the use of an auxiliary sense antenna.

A still further object of my present invention is the advancement, generally, of the art of radio direction finding.

While the antenna system and phase meter to which references have been made are particularly suitable for use in the radio direction finder of my present invention, they are not restricted to such use; but are thought to have general application wherever the need may exist for instrumentalities having like characteristics, as will later become more apparent.

These, and other objects and advantages of my present invention, which will be better understood as the detailed description progresses, are attained, broadly, in the following manner:

I provide an antenna system consisting, preferably, of four omnidirectional antennas, one located at each of the corners of a square, the four corners of said square corresponding to the compass points north, east, south, and west. The output of each of said antennas is independently and differentially modulated in a balanced modulator, preferably located at the base of each antenna, at an audio-frequency rate, the modulating energy applied to the north and south antenna outputs being in quadrature with that applied to the east and west antenna outputs. The four, carrier-suppressed, modulated outputs thus obtained are then combined in a common impedance, preferably located at the center of the antenna system, the energy derived from the north and south antennas and their associated modulators being applied to said impedance in opposition, as is the energy derived from the east and west antennas and their associated modulators. The result of the combination is a carrier-suppressed, low-frequency modulated, radio-frequency signal whose envelope phase is a function of the bearing of the source of said radio-frequency signal. This signal is then detected in a standard radio receiver, and the demodulated output of said receiver is applied to a bearing indicator, consisting of a phase meter, to enable comparison of the phase thereof with a reference phase, for example, the phase of the above mentioned modulating energy.

Said bearing indicator is, preferably, of the cathode-ray type, and includes a sweep generator for producing a diametral-line trace, which is caused to assume an instantaneous length inversely proportional to the instantaneous amplitude of the output of the above mentioned receiver, said trace being rotated about its central

point at an angular velocity equal to that of the above mentioned modulating energy. This produces upon the screen of the cathode-ray tube a propeller-shaped pattern the tips of which, when said screen is properly calibrated in terms of azimuth, indicate the direct and reciprocal directions of arrival of the radio-frequency signal instantaneously under consideration. However, this display is characterized by a 180° ambiguity, and, in order to resolve this ambiguity, it is necessary to add a sense voltage to the modulated input to the above mentioned common combining impedance. Such a sense voltage is preferably obtained by shifting the phase of a portion of the output of each antenna by 90°, so as to obtain a final voltage which is cophasal with the receiver input, adding the phase-shifted voltages, and adjusting the amplitude of the resulting signal to correspond with the amplitude of the modulated portion of the input to said receiver. At the same time, a blanking signal is supplied to the indicator whereby the diametral-line trace is converted into a radial-line trace. The resulting cardioid or half-propeller patterns now appearing upon the indicator screen point to the true bearing of the radio-frequency signal instantaneously under consideration.

In the accompanying specification there is described, and in the annexed drawings shown, what is at present considered a preferred embodiment of the radio direction finders of the present invention. It is, however, to be clearly understood that the present invention is not limited to said embodiment, inasmuch as changes therein may be made without the exercise of invention and within the true spirit and scope of the claims hereto appended.

In said drawings:

Figure 1 is a block diagram of a portion of a radio direction finder assembled in accordance with the principles of my present invention, said diagram including the major components of said direction finder from the antenna system to the receiver;

Figure 2 is a block diagram of a bearing indicator assembled in accordance with the principles of my present invention, and intended, primarily, for use with that portion of the system generally shown in Figure 1;

Figures 3, 4, and 5 show the wave shapes of the outputs of some of the more important components shown in Figures 1 and 2;

Figure 6 illustrates various types of indicator displays resulting from the operation of the radio direction finder of my present invention under varying circumstances;

Figure 7 is a perspective view of the antenna system preferably utilized with the radio direction finder of my present invention;

Figure 8 is a circuit diagram of the balanced modulators and sense-voltage amplifiers preferably used for independently modulating the output of each of the four antennas comprising the antenna system shown in Figure 7, and deriving therefrom an appropriate sense voltage;

Figure 9 is a circuit diagram of a phase splitter and two phase inverters for controlling the phase relationships between the inputs to the modulators of Figure 8;

Figure 10 is a circuit diagram of a modulator for controlling the input to the balanced modulators, one of which is shown in Figure 11.

Figure 11 is a circuit diagram of one of the two balanced modulators used to provide the indicator of my present invention with a rotating trace;

Figure 12 is a circuit diagram of a phase-rotation control for properly initially orienting the indicator display with respect to a preselected reference direction;

Figure 13 is a circuit diagram of a pattern-rotating circuit for reorienting the normal indicator display during sense determination; and

Figure 14 is a circuit diagram of a blanking signal generator for appropriately altering the normal indicator display during sense determination.

Referring now more in detail to the aforesaid preferred embodiment of my present invention, and with particular reference to the block diagram of Figure 1 of the drawings, and the wave shapes of Figures 3, 4, and 5 of the drawings, the numeral 20 generally designates an antenna system consisting of four individual, horizontally-omnidirectional antennas N, E, S, and W. These antennas are disposed one at each of the corners of a square and correspond, respectively, to the compass points north, east, south, and west.

The radio frequency field (E), Figure 3A, existing at the center 21 of such antenna system, which will be taken as reference throughout this description, is represented by the equation:

$$E = E_m \sin \omega c t \quad (1)$$

where E_m is the maximum value of the field strength, and ω_c is the angular frequency thereof.

The voltages (e_n , e_s , e_e , e_w), Figures 3B, 3C, 3D, and 3E, respectively induced in the antennas N, S, E, and W are, therefore:

$$e_n = E_m h_e \sin \left(\omega_c t + \frac{2\pi d}{\lambda} \cos \alpha \right) \quad (2)$$

$$e_s = E_m h_e \sin \left(\omega_c t - \frac{2\pi d}{\lambda} \cos \alpha \right) \quad (3)$$

$$e_e = E_m h_e \sin \left(\omega_c t + \frac{2\pi d}{\lambda} \sin \alpha \right) \quad (4)$$

$$e_w = E_m h_e \sin \left(\omega_c t - \frac{2\pi d}{\lambda} \sin \alpha \right) \quad (5)$$

where h_e is the effective height of each antenna, d is the distance of each antenna from the center 21 of the system, γ is the wave length of the carrier, and α is the angle of wave arrival measured clockwise from north.

These antenna voltages are respectively applied to balanced modulators 22, 23, 24, and 25 preferably disposed one at the base of each antenna. As will later be described in detail, each antenna modulator consists, generally, of a pair of parallel-fed, vacuum tube amplifiers the outputs of which are combined, push-pull fashion, in a common combining impedance 26 which, in turn, feeds a conventional receiver 27.

Now the plate currents (i_{p1} , i_{p2}) of the amplifiers of the modulator 22 flow through the combining impedance 26 in opposite directions and may be represented by the equations:

$$i_{p1} = \frac{\mu e_g}{R_p} = e_g Gm_1 \quad (6)$$

$$i_{p2} = \frac{\mu e_g}{R_p} = -e_g Gm_2 \quad (7)$$

where μ is the amplification factor of each tube, e_g is the voltage acting at the grid of each tube, R_p is the plate resistance of each tube, and Gm is the instantaneous grid-to-plate transconductance.

Substituting the value of the voltage e_n (2), de-

ived from the north antenna N, for e_1 (6 and 7), and applying the resulting plate currents (i_{p1}, i_{p2}) to the common combining impedance 26, two component voltage drops (e_{n1}, e_{n2}) are obtained across the receiver input:

$$e_{n1} = E_m h_e Gm_1 Z_t \sin \left(\omega_c t + \frac{2\pi d}{\lambda} \cos \alpha \right) \quad (8)$$

$$e_{n2} = -E_m h_e Gm_2 Z_t \sin \left(\omega_c t + \frac{2\pi d}{\lambda} \cos \alpha \right) \quad (9)$$

where Z_t is the transfer impedance of the load on the modulator.

The sum of the component voltages e_{n1} and e_{n2} (8 and 9), in the absence of any modulating voltages being applied to the modulator 22, obviously is zero. However, by differentially applying an audio-frequency modulating voltage to said modulator, I sinusoidally vary the transconductance (Gm) of each of the amplifiers. This is accomplished in the following manner:

I provide a conventional oscillator 28 for generating an audio-frequency voltage (e_a), Figure 3F, of about 150 C. P. S.:

$$e_a = A \sin \omega_m t \quad (10)$$

where A is the maximum value of the modulating voltage, and ω_m is the angular frequency thereof.

This voltage is fed to a 90° phase splitter 29 to obtain two unbalanced outputs (e_{a1}, e_{a2}), Figure 3G, as follows:

$$e_{a1} = A_1 \cos \omega_m t \quad (11)$$

$$e_{a2} = A_1 \sin \omega_m t \quad (12)$$

These outputs are applied, respectively, to phase inverters 30 and 31, to obtain two pairs of balanced outputs ($e'_1, e'_2; e''_1, e''_2$), Figures 3H and 3I, each pair having its components in 180° phase opposition, and the pairs being in quadrature with each other:

$$e'_1 = -A_2 \cos \omega_m t \quad (13)$$

$$e'_2 = A_2 \cos \omega_m t \quad (14)$$

$$e''_1 = A_2 \sin \omega_m t \quad (15)$$

$$e''_2 = -A_2 \sin \omega_m t \quad (16)$$

As above stated, the effect of applying modulating voltages to the balanced modulators is to vary the transconductance of the amplifiers thereof. The instantaneous transconductance (Gm_1, Gm_2), therefore, of the tubes of the modulator 22 can be expressed:

$$Gm_1 = Gm_0 (1 + A_m \cos \omega_m t) \quad (17)$$

$$Gm_2 = Gm_0 (1 - A_m \cos \omega_m t) \quad (18)$$

where Gm_0 is the average transconductance, and A_m is the modulation factor.

Equations 8 and 9, representing the unmodulated voltage drops (e_{n1}, e_{n2}) across the receiver input resulting from the modulator 22, then, as shown in Figure 4A, become:

$$e'_{n1} = E_m h_e Gm_0 (1 + A_m \cos \omega_m t) Z_t \sin \left(\omega_c t + \frac{2\pi d}{\lambda} \cos \alpha \right) \quad (19)$$

$$e'_{n2} = -E_m h_e Gm_0 (1 - A_m \cos \omega_m t) Z_t \sin \left(\omega_c t + \frac{2\pi d}{\lambda} \cos \alpha \right) \quad (20)$$

The result of combining these voltages, the final output (e'_n), Figure 4B, of the modulator 22; in other words, the input to the receiver due to the north antenna N, is:

$$e'_n = 2E_m h_e Z_t A_m Gm_0 \cos \omega_m t \sin \left(\omega_c t + \frac{2\pi d}{\lambda} \cos \alpha \right) \quad (21)$$

In a similar manner the voltage drops (e'_s, e'_w), Figure 4C, due to the amplifiers of the modulator 23 become:

$$e'_s = E_m h_e Gm_0 (1 - A_m \cos \omega_m t) Z_t \sin \left(\omega_c t - \frac{2\pi d}{\lambda} \cos \alpha \right) \quad (22)$$

$$e'_w = -E_m h_e Gm_0 (1 + A_m \cos \omega_m t) Z_t \sin \left(\omega_c t - \frac{2\pi d}{\lambda} \cos \alpha \right) \quad (23)$$

And the input e'_e , Figure 4D, to the receiver due to the south antenna S, becomes:

$$e'_e = -2E_m h_e Z_t A_m Gm_0 \cos \omega_m t \sin \left(\omega_c t - \frac{2\pi d}{\lambda} \cos \alpha \right) \quad (24)$$

Likewise, the amplifier outputs of the modulator 24 (e'_e, e'_s), Figure 4E and the amplifier outputs of the modulator 25 (e'_w, e'_e), Figure 5A, are:

$$e'_e = E_m h_e Gm_0 (1 + A_m \sin \omega_m t) Z_t \sin \left(\omega_c t + \frac{2\pi d}{\lambda} \sin \alpha \right) \quad (25)$$

$$e'_s = -E_m h_e Gm_0 (1 - A_m \sin \omega_m t) Z_t \sin \left(\omega_c t + \frac{2\pi d}{\lambda} \sin \alpha \right) \quad (26)$$

$$e'_w = E_m h_e Gm_0 (1 - A_m \sin \omega_m t) Z_t \sin \left(\omega_c t - \frac{2\pi d}{\lambda} \sin \alpha \right) \quad (27)$$

$$e'_e = -E_m h_e Gm_0 (1 + A_m \sin \omega_m t) Z_t \sin \left(\omega_c t - \frac{2\pi d}{\lambda} \sin \alpha \right) \quad (28)$$

And combining the modulator voltages e'_e and e'_s , and the modulator voltages e'_w and e'_e , to obtain the inputs (e'_e, e'_w), Figures 4F and 5B, to the receiver due to the east and west antennas E and W we have:

$$e'_e = 2E_m h_e Z_t A_m Gm_0 \sin \omega_m t \sin \left(\omega_c t + \frac{2\pi d}{\lambda} \sin \alpha \right) \quad (29)$$

$$e'_w = -2E_m h_e Z_t A_m Gm_0 \sin \omega_m t \sin \left(\omega_c t - \frac{2\pi d}{\lambda} \sin \alpha \right) \quad (30)$$

I now substitute an antenna constant (K) in Equations 21, 24, 29, and 30:

$$K = 2h_e Z_t A_m Gm_0 \quad (31)$$

Adding the four carrier-suppressed, modulated outputs of the antenna modulators 22, 23, 24, and 25, represented by said Equations 21, 24, 29, and 30 to obtain the resultant input to the receiver ($e_r = e'_n + e'_s + e'_w + e'_e$):

$$e_r = 2E_m K \left[\sin \left(\frac{2\pi d}{\lambda} \cos \alpha \right) \cos \omega_m t + \sin \left(\frac{2\pi d}{\lambda} \sin \alpha \right) \sin \omega_m t \right] \cos \omega_c t \quad (32)$$

In practice, and as previously stated, the spacing d is small compared with the wave length λ . The following approximations may therefore be employed to simplify Equation 32 and to make its physical significance more apparent:

$$\left(\frac{2\pi d}{\lambda} \cos \alpha\right) \approx \sin\left(\frac{2\pi d}{\lambda} \cos \alpha\right)$$

$$\left(\frac{2\pi d}{\lambda} \sin \alpha\right) \approx \sin\left(\frac{2\pi d}{\lambda} \sin \alpha\right)$$

The final input to the receiver (e'_r), Figure 5C, therefore becomes:

$$e'_r \approx E_m K \frac{4\pi d}{\lambda} \cos(\alpha - \omega_m t) \cos \omega_c t \quad (33)$$

From Equation 33 the following may be deduced:

1. When a signal is being received, the radio-frequency input to the receiver is a carrier-suppressed modulated signal having an envelope frequency of

$$\frac{\omega_m}{2\pi}$$

2. The phase of the modulation envelope is a function of the bearing of the signal source.

3. The resultant active voltage of the antenna system is in quadrature with the field at the center of said system, the actual phase of the input to the receiver being, however, somewhat altered by the transfer-phase characteristics of the common combining impedance 26.

4. The signal sensitivity of the antenna system is proportional to the spacing d of the individual antennas from the center of the system and the frequency of the radio-frequency signal instantaneously under consideration.

Now the output of the receiver 27, a demodulated and, preferably, negative-going voltage, as shown in Figure 5D, will be zero when

$$\cos(\alpha - \omega_m t) = 0$$

in other words, nulls occur when:

$$(\alpha - \omega_m t) = \frac{\pi}{2}(2n-1) \text{ radians} \quad (34)$$

where n is any integer.

This fact is availed of in the bearing indicator 32 of my present invention, generally shown in Figure 2 of the drawings, which, as previously stated, is essentially a phase meter for comparing the phase of the rectified envelope obtained from the receiver with a reference phase, namely, the phase of the modulating voltage.

For this purpose, I provide a conventional oscillator 33 for generating a relatively low, radio-frequency voltage, Figure 5E, for example, about 200 kc., which is applied to a control modulator 34, later described in greater detail. Here, said radio-frequency voltage is modulated with the output of the receiver 27, which has been passed through an amplifier 35, to obtain the modulated output shown in Figure 5F. Said modulator output has an envelope phase which is a function of the bearing of the signal source instantaneously under consideration, and an amplitude which is instantaneously inversely proportional to the amplitude of the negative-going output of the receiver 27.

This output is applied, through balanced indicator modulators 36 and 37, which will later be described more in detail, to the deflecting plates H and V of a cathode-ray tube 38, thereby providing the latter with a diametral-line trace whose length is dependent upon the instantaneous

amplitude of the output of the receiver. The diametral-line trace thus obtained is caused to scan a circular area on the screen of the cathode-ray tube 38 at the angular velocity of the modulating energy applied to the modulators of the antenna system 20.

For this purpose, a portion of the output of the audio-frequency oscillator 28 is passed through a pattern-rotating circuit 39, a phase-rotation control circuit 40, and an amplifier and filter 41, the purposes and functioning of which will later be described, and applied to a phase splitter 42 to obtain two voltages in quadrature. These quadrature voltages, after being passed through phase inverters 43 and 44, are applied, differentially, to the balanced modulators 36 and 37. The result is to provide the cathode-ray tube 38 with a rotating field which, in turn, causes the diametral-line trace with which said cathode-ray tube has been provided as above described, to be rotated about its center point.

There now appears upon the screen of the cathode-ray tube a propeller-shaped pattern 45, Figure 6A, comprised of a rotating diametral-line trace, the instantaneous length of which is a function of the amplitude of the output of the receiver 27, and the tips of which correspond to the nulls of the output of said receiver and point, on a calibrated scale 46 with which the screen of said cathode-ray tube is provided, to the direct and reciprocal bearings of the source of the radio-frequency signal instantaneously under consideration.

The pattern is initially properly oriented with respect to the calibrated scale by suitably adjusting the phase of the portion of the output of the oscillator 28 applied to the modulators 36 and 37 by means of the phase-rotation control 40.

Now the display thus far obtained includes an ambiguity of 180° , as have the normal displays of existing radio direction finding systems. It has heretofore been the practice to employ a separate sense antenna to resolve this ambiguity, but I propose to accomplish the same result without the use of such a separate antenna.

From an inspection of Equation 33 it is apparent that if a voltage (e_c) of the form:

$$e_c = E_m K \frac{4\pi d}{\lambda} \cos \omega_c t \quad (35)$$

is added to the voltage (e'_r), represented by said Equation 33, nulls will not be obtained when $\cos(\alpha - \omega_m t) = 0$. Instead, nulls will be obtained when $\cos(\alpha - \omega_m t) = -1$; in other words, when:

$$(\alpha - \omega_m t) = \pi(2n-1) \text{ radians}; \quad (36)$$

where n is any integer.

The spacing between the nulls of the rectified envelope, constituting the output of the receiver 27, will now be equal to 2π radians of the modulating cycle, and I utilize this result to alter the indicator display to resolve the above mentioned ambiguity.

To this end, and returning once again to Figure 1 of the drawings, I apply a portion of the output of each of the antennas N, S, E, and W, respectively to differentiating circuits 47, 48, 50, and 49 whereby signals are obtained which are substantially 90° out-of-phase with the inputs to the respective antenna modulators 22, 23, 24, and 25. These signals are added to each other, upon closing switches 51, 52, 53, and 54, in the combining impedance 26, with the result that a sense signal is applied to the receiver 27 which is substantially cophasal with the modulated

signal e'_r (33). The amplitude of the sense signal is adjusted to a value equal to that of the expression

$$E_m K \frac{4\pi d}{\lambda}$$

in Equation 33.

Simultaneously with the addition of the sense voltage (e_s) to the receiver input (e'_r), the pattern appearing upon the screen of the cathode-ray tube 38 is rotated through 90° by operation of a switch 55, Figure 2, associated with the pattern-rotating circuit 39, and the diametral-line trace resulting in the propeller-shaped indicator display 45 is converted into a radial-line trace. This is accomplished by utilizing a portion of the output of the radio-frequency oscillator 33 to generate, in a blanking signal generator 56, a blanking signal lasting for approximately one-half of the period of the output of said oscillator, which is applied to the intensity grid G of the cathode-ray tube 38. The blanking signal is suitably phased by interposing a phase shifter 57 between the oscillator 33 and the generator 56, and the application of this signal to the tube 38 is controlled by a switch 58. The switches 51, 52, 53, and 54, Figure 1, and the switches 55 and 58, Figure 2, are preferably ganged for simultaneous operation.

The result of applying the sense voltage, obtained as above, to the receiver input is to convert the ambiguous propeller-shaped pattern 45 of Figure 6A to the sense-determining, cardioid pattern 59 of Figure 6B.

As above indicated, if the sense voltage (e_s) is equal to the normal receiver input (e'_r) the receiver output will have a single null per modulation-signal cycle and the display of Figure 6B results. If, however, the sense voltage (e_s) is less than the receiver input (e'_r), the receiver output will have two minima per modulation-signal cycle, but said minima will be unequally spaced in time. The result will be the dual sense-determining pattern 60, shown in Figure 6C. In either case, the ambiguity above referred to will have been resolved.

I have found in practice that sometimes, as a result of low signal intensity or because of unfavorable wave front characteristics the bearing indication is not sharply defined. In order to enhance accuracy of observation under such circumstances I provide the balanced modulators 36 and 37 of the indicator with means to be further explained during the description of the modulator circuit shown in Figure 11, for purposely unbalancing said modulators. Such unbalancing causes the pattern 45 of Figure 6A to become symmetrically split, resulting in the pattern 61, shown in Figure 6D. This display is read at the intersections 62 of the two displaced propeller-shaped patterns rather than at the tips thereof, such manner of reading the display materially increasing the effective operating sensitivity of the indicator.

I have further found in practice that signals are frequently encountered which are characterized by wave-front properties which are unfavorable for direction finding. When this is so, the input to the receiver is not represented by Equation 33, and the nulls of the modulation envelope become obscure, or unequally spaced in time, or both. This automatically causes the indicator display to be periodically drawn in from the outer periphery of the screen and, in addition, unsymmetrically split, as may be seen from

the pattern 63, shown in Figure 6E. However, this does not interfere too greatly with obtaining an accurate bearing on the source; for, by averaging the indications of the two unequal propeller-shaped patterns, the difficulty is largely overcome and a fairly accurate reading is obtained. Or, if the signal is fading, the operator can wait for the instant when the patterns superimpose or become symmetrical and then take a reading as described above for normal operation.

Before passing to a detailed description of the circuits which may be employed in the various components of the direction finder of my present invention, there is an important further feature 15 requiring attention. In certain practical direction-finding situations it becomes desirable to obtain bearings simultaneously on a plurality of signal sources. As indicated in earlier portions of this specification, the antenna system 20, and the modulating system therefor disclosed herein, are such that the output therefrom consists of an entire spectrum of carrier-suppressed, modulated signals with the envelope phase of each signal in the spectrum determined by the direction to the 20 source of that signal. The width of the spectrum may be controlled by adjusting the band-pass characteristics of the combining impedance 26. The modulated output, therefore, can be connected to any desired number of receivers and 25 associated indicators, thereby enabling simultaneous direction finding on any desired number of individual signal sources.

This completes the general description of the direction finder of my present invention and I 30 shall now describe some specific circuits which may be utilized in the main components thereof.

As shown in Figure 7, each of the antennas N, E, S, and W of the antenna system 20 preferably 35 comprises a plurality of telescoping elements 64 rising from housings N', E', S', and W'. Said 40 housings are disposed, in the form of a square, at the outer ends of mutually perpendicular conduits 65, and are receptive, respectively, of the balanced modulators 22, 24, 23, and 25 (Figure 45 1). The conduits 65 encase the connecting leads between said modulators and the common combining impedance 26, the latter being inclosed in a housing 66 disposed at the center of the system.

Each of the antenna modulators 22 to 25 inclusive, as shown in Figure 8, preferably includes 50 a pair of pentode vacuum tubes 67 and 68, the cathodes of which are connected to the opposite ends of a variable resistor 69, and thence, to ground, through the adjustable arm of said resistor 69 and a second variable resistor 70. The 55 input circuit of each of said tubes includes a coupling capacitor 71 and a grounded grid resistor 72; the screen grids thereof are connected to the positive terminal of relatively low-voltage "B" 60 supply, through a dropping resistor 73 of appropriate value, by-passed by a capacitor 74; and the suppressor grids thereof are grounded, as shown. Plate voltage to each of said tubes is supplied 65 through a center-tap in the combining impedance 26, and the plate outputs thereof are combined in said impedance, in opposition.

The tubes of each modulator are parallel fed 70 from the corresponding antenna of the system, and have differentially applied thereto, through resistors 75, appropriately phased, balanced modulating energy from the inverters 38 and 39 (Figure 1). The relative gains of the 75 tubes of each modulator are adjusted by means of the variable resistor 69, and the over-all gain of

each modulator is adjusted by means of the variable resistor 70.

The means for deriving the sense voltage necessary to resolve the ambiguity normally present in the bearing display of any selected signal, referred to in earlier portions of this specification, are associated with the antenna modulators just described. Such means include the differentiating circuits 47, 48, 50, and 49, each such circuit comprising, preferably, a capacitor 76, a resistor 77, and an inductor 78, connected in series between each antenna N, S, E, and W, and ground. The drops across the inductors are applied to pentode vacuum tubes 19, the cathodes of which are grounded through bias resistors 80, and the respective switches 51, 52, 54, and 53. The screen grid of each of these tubes is connected to the low-voltage "B" supply, above mentioned, and the plates of said tubes are all connected to the same side of the combining impedance 26 through coupling resistors 81. In order to maintain proper balance in each antenna modulator, the plate circuits of those tubes thereof which are connected to the opposite side of the impedance 26, include compensating networks, consisting of resistors 82 which are grounded through capacitors 83.

Because of the differentiating actions of the circuits 47 to 50 inclusive, the signals acting at the control grid of each tube 19 are substantially 90° out-of-phase with the received signals at the grids of the modulator tubes 67 and 68. However, the addition of the sense signals in the impedance 26 results in an omnidirectional signal which is substantially cophasal with the resultant modulated signal fed to the receiver 21.

The phase splitter 29 and the phase inverters 30 and 31, utilized to apply properly phased modulating voltages to the antenna modulators 22 to 25 inclusive, may take the form of the circuits shown in Figure 9. As there shown, a portion of the output of the audio-frequency oscillator 28 is applied, in parallel, across a resistor 84, and two networks 85 and 86, the latter constituting said phase splitter 29. The network 85 includes a capacitor 87 and a resistor 88 connected, in series, with a parallel combination of a fixed resistor 89 and a variable resistor 90. The network 86 includes a resistor 91 and a capacitor 92 connected in series. The values of the capacitors 87 and 92 are equal, and the value of the resistor 91 is equal to the equivalent resistance of the resistor 88 and the parallel combination of resistors 89 and 90.

The drop across an appropriate portion of the resistor 90 is applied to a vacuum tube amplifier 93, and the drop across the capacitor 92, which is substantially 90° out-of-phase with the drop across said resistor 90, is applied to a vacuum tube amplifier 94. The cathodes of the tubes 93 and 94 are grounded, respectively, through resistors 95 and 96, and plate potentials are applied to said tubes, respectively, through resistors 97 and 98. The plate output of the tube 93 is applied, through a coupling capacitor 99 and grid resistor 100, to a vacuum tube 101, constituting the inverter 31, and the plate output of the tube 94 is applied, through a coupling capacitor 102 and grid resistor 103, to a vacuum tube 104, constituting the inverter 30. The cathodes of the tubes 101 and 104 are grounded, respectively, through pairs of series connected resistors 105 and 106, and 107 and 108, and plate voltage is supplied to these tubes, respectively, through resistors 109 and 110. Plate and cathode outputs

from the tube 101 are applied, through coupling capacitors 111 and 112, to the antenna modulators 24 and 25, and like outputs from the tube 104 are applied, through coupling capacitors 113 and 114, to the antenna modulators 22 and 23. The component outputs of each tube are 180° out-of-phase with each other, and the dual output of the tube 101 is in quadrature with the dual output of the tube 104.

The radio-frequency control modulator 34, for mixing the bearing-indicating output from the amplifier 35 and the radio-frequency oscillations generated by the radio-frequency oscillator 33, may take the form shown in Figure 10. As there shown, the modulator 34 includes a pentode vacuum tube 115, the cathode of which is grounded through a bias resistor 116 and a variable resistor 117, the latter having applied across the same, the output from the oscillator 33. The output of the bearing amplifier 35 is applied to the control grid of the tube 115 across a grounded grid resistor 119. The screen grid of said tube has a positive potential applied thereto through a resistor 120, by-passed by a capacitor 121, and the suppressor grid thereof is grounded, as shown. Plate potential is applied through a tuned circuit which includes the parallel combination of an inductor 122 and a variable capacitor 123, said parallel combination being resonant to the radio-frequency output of the oscillator 33. The output of the modulator 34 is applied to the indicator modulators 36 and 37.

The indicator modulators 36 and 37, one of which is illustrated in Figure 11, each comprise a pair of pentode vacuum tubes 125 and 126, the cathodes of which are connected to the opposite ends of a variable resistor 127 whose adjustable arm is grounded through a resistor 128.

The variable resistor 127 controls the relative gains of the tubes 125 and 126 and, as indicated in earlier portions of this specification, is used purposely to split the bearing indications on signals which are difficult to read, to enhance the accuracy of observation thereof. The resistors 127 and 128 are by-passed by capacitors 129 and 130.

The control grids of the tubes 125 and 126 are grounded through resistors 131 and 132, and, in addition to being receptive of the output of the control modulator 34, through coupling capacitors 124, are receptive, through resistors 133 and 134, of properly phased modulating voltages from the inverters 43 or 44.

The screen grids of the tubes 125 and 126 have positive potentials applied thereto through a resistor 135, by-passed by a capacitor 136, and the suppressor grids thereof are tied to the cathodes. The plates of said tubes are supplied with positive potentials through a center-tapped tuned circuit which includes inductors 137 and 138 shunted by a capacitor 139, said tuned circuit being resonant to the radio-frequency oscillations fed to the modulators from the radio-frequency control modulator 34. The outputs across the tuned circuit, which are in 180° phase opposition, are applied, through coupling capacitors 140 and 141, to the deflecting plates of the cathode-ray tube 38. Of course, the envelopes of the dual outputs of the modulators 36 and 37 are in phase quadrature.

A satisfactory form for the phase rotation control circuit 40 is shown in Figure 12. It includes a vacuum tube 142, connected as a phase inverter, having its cathode grounded through resistors 143 and 144, its input circuit including a coupling

capacitor 145 and grid resistor 146, and its output circuit including capacitors 147 and 148, and a variable resistor 149 in series therewith. Plate potential is applied through a resistor 150.

The phase of the output across the resistor 149 is controlled by adjusting the value of said resistor, and the control range is governed by the relative impedances of the capacitor 147 and said resistor. The magnitude of said output is substantially constant over said control range, provided the values of the resistors 144 and 150 are small compared to the impedance values of the capacitor 147 and the resistor 149.

Figure 13 shows an appropriate form which the pattern rotating circuit 38 may take. As there shown, the switch 55, which is associated with said circuit, is a double-pole double-throw switch having outer contacts 151, 152, 153, 154 and central contacts 155 and 156. The output of the audiofrequency oscillator 28 is conveyed to the contacts 151 and 154 by conductors 157 and 158, and the contacts 152 and 153 are grounded. Connected between the central contacts 155 and 156 are a capacitor 159 and a resistor 160, the reactance of the capacitor being equal to the resistance of the resistor. The output of the circuit, which is applied to the phase rotation control circuit 40, is taken between the junction of the capacitor and resistor, and ground, so that when the switch is thrown to the right, the phase of the input thereto is retarded 45°, and when the switch is thrown to the left, the phase is advanced 45°. There is, therefore, a relative phase shift of 90° when the switch is thrown from left to right.

I shall now describe a satisfactory circuit for converting the diametral-line trace, normally displayed on the screen of the cathode-ray tube 38 of the indicator, to the radial-line trace, which is observed during sense determination. This circuit, shown in Figure 14, includes the phase shifter 57, switch 58, and blanking signal generator 56.

As hereinbefore stated, the radio-frequency oscillator 33 is conventional, the output thereof being obtained from a tank circuit 161 tuned to the desired frequency. Said output is inductively coupled, through a link 162, to the phase shifter 57. The latter comprises an inductor 163 which is center-tapped to ground, as shown, said inductor being shunted by a series connected variable capacitor 164 and resistor 165. The output of said phase shifter is taken between the junction of said capacitor and resistor, and ground, and is applied, through a coupling capacitor 166 and a grid resistance network 167, to a pentode vacuum tube 168. The cathode of said tube is grounded through the switch 58, and the time constant of the input circuit to the control grid is such as to develop appropriate bias to obtain a substantially negative-going output from the tube. The screen grid is supplied with a proper positive potential through a resistor 169; the suppressor grid is grounded, as shown; and plate voltage is applied through a resistor 170 and radio-frequency choke 171. The output of this circuit is applied through a capacitor 172 to the intensity grid of the cathode-ray tube 38.

This completes the description of some of the circuits which may be employed in the major components of the direction finder of my present invention. Circuits for the remaining components may be entirely conventional and therefore have not been described herein.

It will be noted from all the foregoing that I have provided a radio direction finder which in-

corporates, among others, the following novel and advantageous features:

1. I have provided an omnidirectional, fixed antenna system which is capable of operation over a relatively wide band of frequencies. By means thereof I am able to take bearings on a plurality of sources of signals simultaneously. I have avoided the structural problems and high costs ordinarily associated with conventional directional systems; and I have eliminated the laborious operating techniques and the inaccuracies usually associated with systems requiring manual orientation.

2. I have provided an antenna system which is so designed as to maintain the number of transmission channels employed therewith at a minimum, thereby reducing phasing and impedance matching problems.

3. I have provided an aperiodic, electronic goniometer incorporating means for so modulating the output of the antenna system as to obtain a spectrum of signals the envelope phase of each of which is a function of the bearing of the source thereof.

4. I have provided a bearing indicator, in the form of a phase meter, by means on which an accurate bearing of the source of energy instantaneously under consideration is immediately obtained, and such indicator is so designed that signals, which ordinarily would be considered unfavorable for direction finding, may be accurately read.

5. Finally, I have provided a direction finding system in which sense determination is readily made without the necessity of utilizing an auxiliary sense antenna.

Other objects and advantages of the direction finding system of my present invention will readily occur to those skilled in the art to which the same relates.

I claim:

1. In the method of determining the direction of arrival of wave energy, those steps which include: deriving a plurality of signals from said wave energy at a plurality of points, said points being so physically disposed with respect to a predetermined reference point and with respect to each other that the phase of each of said signals is a continuous function of the bearing of the source of said wave energy with respect to a fiducial line extending from said reference point in a predetermined direction; sinusoidally modulating each of said signals independently at a single frequency which is a minor fraction of that of said wave energy, with the modulation applied to at least one pair of said signals differing in phase from that applied to at least one other pair; combining the resulting modulated components to obtain a resultant modulated signal having an envelope phase which is a function of the bearing of said source with respect to said fiducial line; and comparing said envelope phase with the phase of the modulating energy.

2. In the method of determining the direction of arrival of wave energy, those steps which include: deriving a plurality of signals from said wave energy at a plurality of points, said points being so physically disposed with respect to a predetermined reference point and with respect to each other, that the phase of each of said signals is a continuous function of the bearing of the source thereof with respect to a fiducial line extending from said reference point in a predetermined direction; sinusoidally modulating each of said signals independently at a frequency

which is a minor fraction of that of said wave energy, with the modulation applied to at least one pair of said signals in quadrature with that applied to at least one other pair; combining the resulting modulated components of each of said signals to obtain a plurality of equal-amplitude, carrier-suppressed signals, one corresponding to each of said first-named signals; combining said carrier-suppressed signals to obtain a resultant modulated signal having an envelope phase which is a function of the bearing of said source of said first-named signals with respect to said fiducial line; and transforming said resultant modulated signal into a visual indication of the bearing of the source of said wave energy.

3. In the method of determining the direction of arrival of wave energy, those steps which include: deriving a plurality of signals from said wave energy at a plurality of points, said points being so physically disposed with respect to a predetermined reference point and with respect to each other that the phase of each of said signals is a continuous function of the bearing of the source thereof with respect to a fiducial line extending from said reference point in a predetermined direction; sinusoidally modulating each of said signals independently at a single frequency which is a minor fraction of that of said wave energy, with the modulation applied to at least one pair of said signals differing in phase from that applied to at least one other pair; combining the resulting modulated components of each of said signals to obtain a plurality of modulated signals, one corresponding to each of said first-named signals; combining said modulated signals whereby a resultant modulated signal is obtained, the phase of whose modulation envelope is a function of the bearing of the source of said first-named signals with respect to said fiducial line; transforming said resultant modulated signal into a visual indication of the direct and reciprocal bearings of the source of said wave energy; so combining unmodulated portions of an even number of said first-named signals as to derive a sense-determining signal; and combining said sense-determining signal with said resultant modulated signal to resolve the ambiguity in said visual indication.

4. A radio direction finder comprising: an antenna system for deriving a plurality of signals from a single source of wave energy, said antenna system including four independent collector elements, one at each corner of a square and each adapted to receive from said single source of wave energy a signal having a phase which is a continuous function of the bearing of said source of wave energy with respect to a predetermined reference direction; means for sinusoidally and independently modulating each of said signals to obtain a plurality of carrier-suppressed signals the phase of each of which is a progressive function of said bearing; means for combining said carrier-suppressed signals to obtain a resultant modulated signal the phase of whose envelope, relative to the phase of the source of said modulating means is a function of said bearing; and a phase meter for comparing the relative phases of said envelope and said modulating means.

5. A radio direction finder comprising: an antenna system for deriving a plurality of signals from a single source of wave energy, each signal so derived having a phase which is a continuous function of the bearing of said source of wave energy with respect to a predetermined reference

direction; means for applying sinusoidal modulation of a single frequency to each of said signals independently and to pairs of said signals in different phases and thereby obtain a plurality of modulated signals the phase of each of which is a function of said bearing; means for combining said modulated signals to obtain a resultant modulated signal the phase of whose envelope, relative to the phase of the source of said modulation, is a function of said bearing; a radio receiver; and a cathode-ray tube provided with a rotating field having an angular velocity harmonically related to the angular frequency of said source of modulation and receptive of the output of said receiver for comparing the relative phases of the envelope of said resultant signal and said source of modulation.

6. A radio direction finder comprising: an antenna system for deriving a plurality of signals from a single source of wave energy, said antenna system including four independent, omnidirectional collector elements, one at each corner of a square and each adapted to receive from said single source of wave energy a signal the phase of which is a continuous function of the bearing of said source of wave energy with respect to a predetermined reference direction; means for applying sinusoidal modulation of a single frequency to each of said signals independently and to pairs of said signals in phase quadrature to obtain a plurality of modulated, carrier-suppressed signals the phase of each of which is a function of said bearing; means for combining said carrier-suppressed signals to obtain a resultant modulated signal the phase of whose envelope, relative to the phase of the source of said modulation, is a function of said bearing; a radio receiver upon which said resultant signal is impressed; and a cathode-ray tube provided with a rotating field under the control of said sinusoidal modulation and having an angular velocity equal to the angular frequency of said source of modulation, and receptive of the output of said receiver, for comparing the relative phases of the envelope of said resultant signal and said source of modulation.

7. A radio direction finder comprising: an antenna system for deriving a plurality of signals from a single source of wave energy, each signal so derived having a phase which is a function of the bearing of said source of wave energy with respect to a predetermined reference direction; means for applying sinusoidal modulation of a single frequency to each of said signals independently to obtain a plurality of modulated signals the phase of each of which is a function of said bearing; means for combining said modulated signals to obtain a resultant modulated signal the phase of whose envelope, relative to the phase of the source of said modulation, is a function of said bearing; means, receptive of said modulation envelope, for transforming the same into visual indicia of the direct and reciprocal bearings of said source of wave energy; and means for resolving the ambiguity in said visual indicia; said last named means including means for deriving a sense-determining signal from a combination of unmodulated portions of an even number of said first-named signals, and means for mixing said sense-determining signal with said resultant modulated signal.

8. A radio direction finder comprising: an antenna system for deriving a plurality of signals from a single source of wave energy, each signal so derived having a phase which is a function of the bearing of said source of wave energy with

respect to a predetermined reference direction; means for applying sinusoidal modulation of a single frequency to each of said signals independently and to pairs of said signals in phase quadrature to obtain a plurality of modulated, carrier-suppressed signals the phase of each of which is a function of said bearing; means for combining said carrier-suppressed signals to obtain a resultant modulated signal the phase of whose envelope, relative to the phase of the source of said modulation, is a function of said bearing; a cathode-ray tube, provided with a rotating field having an angular velocity equal to the angular frequency of said source of modulation, and receptive of said modulation envelope, for transforming the latter into visual indicia of the direct and reciprocal bearings of said source of wave energy; and means for resolving the ambiguity in said visual indicia, said last named means including means for deriving a sense-determining signal from a combination of unmodulated portions of an even number of said first-named signals, and means for mixing said sense-determining signal with said resultant modulated signal.

9. A phase meter comprising: a cathode-ray tube; means for providing said cathode-ray tube with a rapidly recurring diametral-line trace; means for rotating said trace at an angular velocity harmonically related to the angular frequency of the wave whose phase is to be determined; means for altering the instantaneous length of said trace in proportion to the instantaneous amplitude of the wave whose phase is to be determined; and means for comparing the angular position of said trace, with respect to a predetermined reference line, when the length of said trace is a maximum or minimum.

10. In a radio direction-finding system, wherein the direct and reciprocal bearings of the source of a selected carrier are implicit in an output voltage (e'_r) expressed by the approximate relation

$$e'_r \simeq E_m K \frac{4\pi d}{\lambda} \cos(\alpha - \omega_m t) \cos \omega_c t$$

where

E_m is the maximum value of said carrier, K and d are constants of said system, λ is the wave length of said carrier, α is the angle of arrival of said carrier with respect to a predetermined reference direction, ω_m is the angular frequency at which said carrier is locally modulated, and ω_c is the angular frequency of said carrier;

means for resolving the ambiguity in the indicated direction of arrival of said carrier comprising: spaced-aerial means for deriving from said carrier, and adding to said output voltage, a sense-determining voltage (e_c) expressed by the approximate relation

$$e_c \simeq E_m K \frac{4\pi d}{\lambda} \cos \omega_c t$$

where the symbols are as defined above.

11. In a radio direction-finding system, wherein the direct and reciprocal bearings of the source of a selected carrier are implicit in an output voltage (e'_r) expressed by the approximate relation

$$e'_r \simeq E_m K \frac{4\pi d}{\lambda} \cos(\alpha - \omega_m t) \cos \omega_c t$$

where

E_m is the maximum value of said carrier, K and d are constants of said system, λ is the wave length of said carrier, α is the angle of arrival of said carrier with respect to a predetermined reference direction, ω_m is the angular frequency at which said carrier is locally modulated, and ω_c is the angular frequency of said carrier;

means for resolving the ambiguity in the indicated direction of arrival of said carrier comprising: means for deriving from said carrier an even number of signals each of which has a phase which is a function of the direction of arrival of said carrier; and means for combining said signals with each other to obtain a sense-determining voltage (e_c) expressed by the approximate relation

$$e_c \simeq E_m K \frac{4\pi d}{\lambda} \cos \omega_c t$$

where the symbols are as defined above, and adding the same to said output voltage.

12. In a radio direction-finding system, wherein the direct and reciprocal bearings of the source of a selected carrier are implicit in an output voltage (e'_r) expressed by the approximate relation

$$e'_r \simeq E_m K \frac{4\pi d}{\lambda} \cos(\alpha - \omega_m t) \cos \omega_c t$$

where E_m is the maximum value of said carrier,

35 K and d are constants of said system, λ is the wave length of said carrier, α is the angle of arrival of said carrier with respect to a predetermined reference direction, ω_m is the angular frequency at which said carrier is locally modulated in said system, and ω_c is the angular frequency of said carrier;

means for resolving the ambiguity in the indicated direction of arrival of said carrier comprising: means for deriving from said carrier an even number of signals each of which has a phase which is a function of the direction of arrival of said carrier; means for differentiating said signals; and means for combining the differentiated signals with each other to obtain a sense-determining voltage (e_c) expressed by the approximate relation

$$e_c \simeq E_m K \frac{4\pi d}{\lambda} \cos \omega_c t$$

55 where the symbols are as defined above, and adding the same to said output voltage.

13. An antenna system comprising: four independent antenna elements, one at each corner of a square; a balanced modulator associated with each of said antenna elements; a common impedance; and transmission lines for conveying signals between each of said balanced modulators and said common impedance; and a source of sinusoidal modulating potentials of a single frequency for controlling said balanced modulators, and means to phase displace with respect to each other the potentials fed to alternate balanced modulators.

65 14. A system as set forth in claim 13, wherein said phase displacement is 90°.

15. The method as set forth in claim 3, wherein the step of sinusoidally modulating each of said signals also suppresses the carrier.

75 16. The method as set forth in claim 3, wherein the modulation applied to said one pair of said

signals is in phase quadrature with the modulation applied to said other pair.

17. The method as set forth in claim 3, wherein the step of sinusoidally modulating each of said signals also suppresses the carrier, and wherein the modulation applied to said one pair of signals is in phase quadrature with said other pair.

18. In a direction finder having an antenna system comprised of spaced collector elements, means for deriving a sense-reference signal including means for deriving a signal from each of an even number of said spaced collector elements, means for combining the signals so derived, means for adjusting the phase and amplitude of the combined signal and means for combining 15 said combined signal with the output of said antenna system.

19. In a direction finder having an antenna system comprised of spaced collector elements, means for deriving a sense-reference signal without the use of an auxiliary sense antenna including means for deriving a signal from each of an even number of said spaced collector elements, means for shifting the phase of each signal so derived and means for combining the phase-shifted signals with the output of said antenna system.

20. A phase meter as set forth in claim 9, including means for resolving the ambiguity of the indication including means for converting said diametral-line trace into a radial-line trace and means for shifting the phase of rotation of said radial-line trace.

21. A phase meter as set forth in claim 9, including means for unbalancing the rotation of 35 said diametral-line trace to produce symmetrical splitting of said indicating display to enhance the observational accuracy thereof.

22. A phase meter as set forth in claim 9, including means for unbalancing the rotation of 40 said diametral-line trace to produce the splitting of said indicating display whereby the observational accuracy thereof is enhanced, means for resolving the ambiguity of the indication including means for converting said diametral-line 45 trace into a radial-line trace, and means for shifting the phase of rotation of said radial-line trace.

23. A radio direction finder comprising: four independent collector elements having identical horizontal response characteristics, identically oriented; four balanced modulators, one associated with each of said collector elements; a two-phase source of modulating signals of substantially sinusoidal waveform; means for applying said modulating signals to each of said balanced modulators in such a manner that alternate balanced modulators receive modulating signals of different phase; a radio receiver; means for connecting the outputs of said balanced modulators to the input of said receiver; and a bearing indicator receptive of the output of said receiver, said bearing indicator comprising: a cathode-ray tube, a source of high-frequency signal, means for controlling the amplitude of said high-frequency signal in accordance with the output of said receiver; two balanced modulators receptive of the controlled high-frequency signal; a two-phase source of low-frequency modulating signals, harmonically-related to said first-named modulating signals and applied to said balanced modulators in different phases; and means for utilizing the

outputs of said balanced modulators to deflect the beam of said cathode-ray tube to produce visual bearing indications.

24. An indicator of the relative phase between a first periodic signal and a second periodic signal, comprising: a cathode-ray tube, a source of deflection signal having a frequency higher than the frequency of said first and second signals, means for controlling the amplitude of said deflection signal in accordance with the amplitude of said first periodic signal, two balanced modulators, each receptive of the output of said last-named means, means for deriving a pair of phase-displaced signals from said second periodic signal, means for controlling said balanced modulators with said phase-displaced signals, respectively, and means responsive to the outputs of said balanced modulators for deflecting the beam of said cathode-ray tube.

25. An indicator as set forth in claim 24, including means for unbalancing said balanced modulators.

26. An indicator as set forth in claim 24, including means for blanking the beam of said cathode-ray tube during a portion of the period of said deflection signal.

27. An indicator as set forth in claim 24, including means for unbalancing said balanced modulators, and means for blanking the beam of said cathode-ray tube during a portion of the period of said deflection signal.

28. An indicator of the relative phase between a first periodic signal and a second periodic signal comprising: a cathode-ray tube having a pair of orthogonally-related beam deflecting means, a source of deflection signal having a frequency higher than the frequency of said signals, means for controlling the amplitude of said deflection signal in accordance with the amplitude of said first periodic signal, a pair of balanced modulators, each receptive of the output of said last-named means, means for deriving a second pair of phase displaced signals from said second periodic signal, means for exciting each of said balanced modulators with a different one of said second pair of signals, and means for applying the output of each balanced modulator to a different one of said beam deflecting means for deflecting the beam of said cathode-ray tube.

29. An indicator as set forth in claim 28, wherein said second pair of signals is phase displaced 90°.

30. An indicator as set forth in claim 29, including means for unbalancing said balanced modulators.

Certificate of Correction

Patent No. 2,476,977

July 26, 1949

PAUL G. HANSEL

It is hereby certified that errors appear in the printed specification of the above numbered patent requiring correction as follows:

In the drawings, Sheet 4, Fig. 4, opposite the letter "D", left-hand portion of the equation reading,

" $\epsilon_o = 2E_m$ " read $\epsilon_o = -2E_m$

column 3, line 22, for the word "supplied" read *applied*; column 4, line 48, for "γ" read λ; line 68, Equation 7, for that portion reading

$$i_{p2} = \frac{\mu e_s}{R_p} \quad \text{read} \quad i_{p2} = -\frac{\mu e_s}{R_p}$$

column 5, line 33, Equation 11, for that portion reading " $= A_1$ " read $= -A_1$; column 7, line 2, for "γ" read λ; column 8, line 57, for "integer" read *integer*; column 14, line 75, before "frequency" insert *single*;

and that the said Letters Patent should be read with these corrections therein that the same may conform to the record of the case in the Patent Office.

Signed and sealed this 31st day of January, A. D. 1950.

[SEAL]

THOMAS F. MURPHY,
Assistant Commissioner of Patents.
